UNITED STATES PATENT OFFICE

GUSTAV EHRENZWEIG, OF NEW YORK, N. Y.

DESIGN FOR A TEXTILE FABRIC

Application filed July 10, 1929. Serial No. 31,996. Term of patent 3½ years.

To all whom it may concern:

Be it known that I, GUSTAV EHRENZWEIG, a citizen of the United States, and resident of New York, county and State of New York, have invented a new, original, and ornamental Design for Textile Fabrics, of which the following is a specification, reference being had to the accompanying drawing, forming part thereof, and in which the figure is a plan view of a section of the fabric showing my new design.

A complete unit of my design is enclosed within the area A, A', B, B', and this unit is repeated in the relation wherein the junction of one set of similar angles are designated by the unprimed letters A, B, C, etc., and the other set of similar angles by the primed letters A', B', C', etc.

I claim:

The ornamental design for a textile fabric, as shown and described.

GUSTAV EHRENZWEIG.
